UNITED STATES PATENT OFFICE.

FREEMAN E. NUTTING, OF FLORENCE, MASSACHUSETTS.

RACK.

SPECIFICATION forming part of Letters Patent No. 471,885, dated March 29, 1892.

Application filed January 4, 1892. Serial No. 416,924. (No model.)

To all whom it may concern:

Be it known that I, FREEMAN E. NUTTING, of Florence, in the county of Hampshire and State of Massachusetts, have invented certain new and useful Improvements in Racks; and I do hereby declare the following to be a full, clear, and exact description of the invention, such as will enable others skilled in the art to which it appertains to make and use the same.

10 My invention relates to an improvement in racks, the object being to provide a simple and inexpensive device adapted to grasp and securely hold articles, such as pens, pencils, tickets, memoranda, fabrics, and other articles 15 of like nature, and which will admit of the article being readily inserted and removed without danger of injury thereto.

15 A further object is to provide a device which will admit of its being quickly attached 20 to a desk or other object, as desired.

With these ends in view my invention consists in certain novel features of construction and combinations of parts, as will be herein-after more fully described, and pointed out in 25 the claims.

In the accompanying drawings, Figure 1 is a view of my invention, and Fig. 2 is a section of the same.

20 A represents a strip of sheet metal corrugated transversely and bent in serpentine form, as shown in the drawings. Each fold of the sheet-metal strip A is provided centrally with an opening or hole b, through which passes a rod B. The passage of this 25 rod centrally through the sheet-metal strip forms two sets or series of jaws, all of which are designed for and capable of use at the same time. To the outer end of rod B is secured a knob C, which latter can be ornamented in any desired manner, while the other 30 or opposite end is screw-threaded. A washer d rests against the inner end of the metal strip A and is held against displacement by means of the nut or other fastening device e, 35 which latter is secured to the rod B a slight distance in the rear of the screw-threads. This washer and the knob or handle prevent the strip of metal from elongating, and hence prevent the jaws formed by bending the strip 40 from opening or separating except when pressure is applied either against the jaws or by

forcibly withdrawing the object held by the jaws.

By bending the metal strip in serpentine form and passing the rod B centrally through each fold of the metal strip both sides of the rack thus formed are identical in construction and can be used for holding pens, pencils, and many other articles of merchandise. It will also be seen that by corrugating the metal strip A, as shown, greater elasticity is imparted to the rack and the articles grasped will be more firmly held against displacement than has heretofore been accomplished with racks made of a flat piece of sheet metal. 65

The size of my device can be varied to suit the demands of the trade and can also be ornamented in numerous ways, so that it will present a neat and attractive appearance, and when it is desired to attach the rack to a desk, 70 wall, or other furniture the screw end of the rod is secured in the desired place. The rack is particularly well adapted for holding pens or pencils; but it will be observed that the rack is well adapted for displaying articles 75 of merchandise, such as gloves, handkerchiefs, laces, &c.

It is evident that numerous slight changes in the constructive details of my device might be resorted to without departing from the 80 spirit and scope of my invention. Hence I would have it understood that I do not wish to confine myself to the exact form of construction shown and described, but consider myself at liberty to make such slight changes 85 and alterations as fairly fall within the spirit and scope of my invention.

Having fully described my invention, what I claim as new, and desire to secure by Letters Patent, is—

90 1. A rack for supporting pens, pencils, and the like, comprising a metal strip folded in serpentine folds and a rod passed loosely through these folds a suitable distance from the ends, so that space is left on each side of the rod for the support of the article to be held, substantially as set forth.

95 2. As an article of manufacture, a rack for supporting pens, pencils, and the like, comprising a corrugated strip of metal folded back and forth, a rod passing loosely through each fold a sufficient distance from each end

thereof to leave a support on each side for the article to be held, and means for preventing the elongation of the strip beyond a certain point, substantially as set forth.

5 3. The combination, with a metal strip bent in serpentine form, of a rod passing through the bent strip and provided at one end with a knob and at its other end with screw-threads, substantially as set forth.

10 4. The combination, with a corrugated metal strip bent in serpentine form, forming a series of spring-jaws, of a rod passing through said

bent strip, as shown, and provided at one end with a knob and at its other end with screw-threads, and means for preventing elongation or straightening of the bent metal strip, substantially as set forth. 15

In testimony whereof I have signed this specification in the presence of two subscribing witnesses.

FREEMAN E. NUTTING.
